(57) **CLAIM**

I claim the ornamental design for a vanity having child's pull-out step, as shown and described.

DESCRIPTION

FIG. 1 is a perspective view of a vanity having child's pull-out step showing my new design showing the step extended;

FIG. 2 is a front elevational view thereof;

FIG. 3 is a rear elevational view thereof;

FIG. 4 is a right side elevational view thereof showing the step extended, the left side elevational view being a mirror image thereof;

FIG. 5 is a top plan view thereof; and,

FIG. 6 is a bottom plan view thereof showing the step extended.
